GRINDING MACHINE

Jacob Decker, Cincinnati, and Albert D. C. Stuckey, Hamilton, Ohio, assignors to The Cincinnati Milling Machine Co., Cincinnati, Ohio, a corporation of Ohio

Application August 13, 1942, Serial No. 454,682

17 Claims. (Cl. 51—165)

This invention relates to grinding machines and more particularly to an improved automatic infeeding mechanism for the grinding wheels of such machines.

One of the objects of this invention is to provide an improved automatic infeeding mechanism for controlling the movement between a grinding wheel and a work piece in such a manner that the grinding wheel will execute a complete cycle of rapid advancing to the work, moving at a slow feed rate to grind the work to size and of automatically returning to its starting position.

Another object of this invention is to provide an improved hydro-mechanical transmission for executing infeed cycles in which the actuating force is hydraulic and the controlling force is mechanical.

A further object of this invention is to provide an improved power operated infeed mechanism which is suitably interlocked with the table traverse mechanism so that inadvertent power or manual movement of the table is prevented during operation of the cycle.

Other objects and advantages of the present invention should be readily apparent by reference to the following specification, considered in conjunction with the accompanying drawings forming a part thereof and it is to be understood that any modifications may be made in the exact structural details there shown and described, within the scope of the appended claims, without departing from or exceeding the spirit of the invention.

Referring to the drawings in which like reference numerals indicate like or similar parts:

Figure 1 is a front elevation of a grinding machine embodying the principles of this invention.

Figure 2 is a vertical section through the machine shown in Figure 1 with suitable parts broken away to show the mechanical part of the transmission for feeding the grinding wheel.

Figure 3 is a vertical section through the machine as viewed on the line 3—3 of Figure 1 showing the table traversing mechanism.

Figure 4 is a detail section on the line 4—4 of Figure 1.

Figure 5 is a diagrammatic view of part of the hydraulic control circuit.

Figure 6 is a diagrammatic view of the remainder of the hydraulic control circuit and more particularly the table control mechanism.

Figure 7 is a section on the line 7—7 of Figure 2.

Figure 8 is a section on the line 8—8 of Figure 7.

Figure 9 is an enlarged detail view of a multiple position stop for determining the angularity of the feed rate control cam.

Referring to Figure 1 of the drawings the reference numeral 10 indicates the bed of a grinding machine embodying the principles of this invention. The upper part of the front of the bed 10 is provided with a pair of guideways 11 and 12 as more particularly shown in Figure 3 for receiving and guiding a work table 13 which is utilized for traversing a work piece relative to the grinding wheel 14 shown in Figures 1 and 2. The grinding wheel is suitably supported for rotation on the wheel slide 15 and conventional means not shown are carried by the slide for driving the grinding wheel.

The table 13 is actuated by a hydraulic motor 20 in the form of a cylinder 15' and a piston 16, Figure 6, the piston being connected by a piston rod 17 to the table 13. The admittance and exhaust of fluid pressure to the cylinder 15' is controlled by a table control valve, various sections 25 through which are indicated by the reference numerals 18, 19, 20 and 21 in Figure 6 of the drawings. This valve has a rotatable plunger 23 to which the control lever 24, shown in Figure 1, is operatively connected through gearing 24', 30 whereby the lever rotates in an opposite direction to the valve plunger 23. This lever has a central or stop position which is the position shown, a running position indicated by the dash and dot line 25 which is to the left of the stop position, 35 and a third position indicated by the dash and dot line 26 which is to the right of the stop position and which is utilized to effect automatic retraction of the grinding wheel.

The wheel head is provided with a cylinder 27, 40 Figures 2 and 5, for receiving a rack piston 28. A pinion 29 is secured to the upper end of a vertical shaft 30 in mesh with the rack portion 31 of the piston 28 and the lower end of the shaft is provided with a worm wheel 32 which intermeshes with a worm 33. Attention is invited to the fact that the shaft 30 is journaled in the bed 10 and therefore is incapable of any relative bodily movement with respect to the bed while the rack piston is capable of relative bodily movement with respect to the wheel head 15.

Also the worm 33 is supported for relative axial movement with respect to the bed 10 by a piston 34 and a journal 35 which are formed integral with opposite ends of the worm. The piston 34 55 slides in a cylinder 36 while the journal 35 is

capable of rotation or axial movement relative to the bearing 37 which is carried by the bed.

The piston and cylinder 27, 28 are utilized in effecting rapid traverse movement of the wheel head, while the axial movement of the worm 33 is utilized for effecting feeding movements of the wheel head. Rotation of the worm 33 is utilized for effecting adjustment of the wheel head relative to its actuating mechanism to change the final or size determining position of the grinding wheel.

In an automatic infeed cycle of the grinding wheel, the wheel head is first advanced at a rapid traverse rate to bring the wheel up to the work. A feed rate is then instituted which causes the work to be ground to size and then after a slight dwell to allow the grinding wheel to clean up, automatic reversal takes place causing the wheel head to be returned and stopped.

The hydraulic control circuit in Figure 5 has the various parts shown in the position which they assume just prior to the automatic reversal. In order to more clearly understand how these movements are obtained let it be assumed that the wheel head is in a retracted position. Since the cylinder 27 is divided into two portions the forward portion of the cylinder will be indicated by the reference numeral 38 and the rear portion of the cylinder will be indicated by the reference numeral 39. The piston portion which slides in the cylinder 38 will be indicated by the reference numeral 40 and the piston portion which slides in the cylinder 39 will be indicated by the reference numeral 41. When the wheel head is in a retracted position, fluid pressure has been connected to the cylinder 39. Since the pinion 29 is held against rotation by its locking connection with the worm 33, which in turn holds the rack piston 28 and thereby the piston 41 against bodily movement, pressure in cylinder 39 will force the slide 15 to the rear.

It must be remembered, however, that the forward end of the piston 40 will engage the end of cylinder 38 to limit or stop the movement and that once contact is established between the piston 40 and the end of cylinder 38, the rack piston 28 and slide 15 may be considered as a single entity so that torsional strain on the pinion 29 is immediately relieved. Further, the pinion 29 may be rotated to effect bodily movement of the wheel head 15 in either direction and the only resistance is the friction of the slide.

It has been stated that the worm 33 was capable of axial movement relative to the bed, but this movement is limited in extent and only sufficient to effect the feed or stock removal operation. The cylinder 36 is connected to a source of pressure at all times, and since the cylinder is part of the bed the piston 34, as well as the worm 33, are constantly urged toward the right as viewed in Figure 2. An anti-friction thrust bearing 42 is interposed between a shoulder 43 formed on the end of the journal 35, and a thrust plate 44 attached to the stationary part of the bed. The plate 44 serves as a positive stop to determine the final position of the wheel and thereby the size of the work.

The axial movement of the worm 33 under the action of the piston 34 is controlled by an infeed control cam 45 which is reciprocable across the axis of the worm, and as the cam face recedes, it permits the worm to advance. The cam face recedes sufficiently at the end of its stroke to permit the worm to engage the positive stop.

If any additional movement is necessary, the worm must be rotated by the handwheel 46 which is connected through gearing 47 to the shaft 48. The shaft 48 is connected to the piston rod 49 of piston 34 by a slidable joint 50 which permits relative axial movement between the shaft 48 and the rod 49.

It will thus be seen that the rack 28 is normally locked with the wheel head and that the worm 33 is locked between the cam 45 and the hydraulic pressure acting on the piston 34 so that during rotation of the hand wheel the effect is the same as if no sliding connections existed between the various parts and the wheel head may be adjusted in either direction. Such adjustment changes the zone of operation of the grinding wheel as for different sizes of work without changing the length of its rapid traverse or feed movements.

10 To effect automatic operation of the wheel-head, fluid pressure is admitted to the forward cylinder 38 and the rear cylinder 39 is connected to exhaust whereby the fluid pressure reacts against the piston 40 which is held against movement by the pressure in cylinder 36. The wheel head advances relative to the rack piston 28 until it hits the rear end of piston 41 whereby it is positively stopped and once again the piston and the wheel head become a single unit.

15 20 Further advancing is effected at a feeding rate by moving the cam 45 in the direction of arrow 51 as viewed in Figure 5, thereby causing the face of the cam to recede whereby the fluid pressure in cylinder 36 will urge the worm 33 toward the right and cause movement of the wheel head through the rack piston 28 toward the left, all as viewed in Figure 5, thereby feeding the grinding wheel 14 toward the work.

25 The length of the rapid traverse movement may be varied by adjusting the set screw 52 which is threaded in the end of cylinder 39 and locked in position by a locking nut 53. Normally, once this adjustment has been made it would not be necessary to change it. The length of the rapid traverse movement should, of course, be so adjusted as to permit sufficient clearance between the wheel and the work when the wheel head is in its extreme rear position to permit loading and unloading of the work without danger of hitting the wheel.

30 35 The control circuit shown in Figures 5 and 6 are for governing these movements automatically and sequentially whereby the grinding wheel will execute a complete automatic cycle of rapid traversing and feeding in to the required size and returning after the grinding operation has been completed. This cycle is initiated by the operator who throws a lever to a starting position after which the cycle is executed and the lever automatically returned to its stop position.

40 45 This cycle control lever is indicated by the reference numeral 54 in Figure 1 where it is shown mounted on the right hand side of the machine. This lever is connected to the end of a valve plunger 55, a control portion of which is indicated by the reference numeral 56 in Figure 5. The valve is indicated generally by the reference numeral 57 and is provided with a constant pressure port 58 which is supplied through channel 59 from a pump 60 which has an intake 61 for withdrawing oil from a reservoir 62. A relief valve 63 is connected to the output channel 59 of the pump for controlling the pressure therein.

50 55 60 65 70 75 The valve is shown in a running position at which

time the lever 54 assumes the position indicated by the dot and dash line 64. In the stop position of the valve, the lever assumes the position indicated by the line 65, and the vane 66 assumes a position in which the port 58 is connected to a port 67 and thereby through channel 68 to cylinder 49. This holds the wheel head in its retracted position as previously explained. By rotation of the lever from the position 65 to the position 64, the pressure port 58 is connected to port 69 and thereby to channel 70 to start the automatic infeed cycle.

The channel 70 has a branch connection 71 to port 72 of an infeed control valve 73 but the plunger 74 of this valve is normally held in a right hand position by a spring 75 and therefore the port 72 is closed. The fluid in channel 71 may continue, however, through the annular groove 76 in the sleeve of the valve 73 to passage 77 and port 78 of a reversing valve 79.

The plunger 80 of this valve is normally held in the position shown to close the port 78 by pressure from the pump 60 which is connected to port 81 and thereby through annular groove 82, and radial port 83 to an internal bore 84 which serves as a cylinder, the bore being closed by a fixed piston rod 85.

The channel 70 is also connected through a resistance 86 to port 87 of a footstock control valve 88 whereby the fluid pressure enters the upper end of the valve and forces the plunger 89 downward against a spring 90. The fluid pressure entering the chamber 91 in the upper end of the valve is able to continue through port 92, after the plunger moves down, and through channel 93 to port 94 located in the right hand end of the infeed control valve 73, and to pressure switch 95, operation of which initiates rotation of the machine headstock.

Shifting of the footstock valve plunger 89 also interconnects a pair of ports 96 and 97, the latter being connected by channel 98 to a tailstock center operating cylinder 99. Normally, the port 97 is connected to the pressure port 100 by the annular groove 101 whereby pressure exists in cylinder 99 to hold the tailstock center 102 in a retracted position against the resistance of a spring 103. In other words, a piston 104 responsive to the pressure in cylinder 99 actuates the tailstock center through a pivoted crank 105 which is rotatable about a fixed pivot 106. The port 96 is connected to a return line 107 which leads to the reservoir 62. A low pressure relief valve 108 is connected in this line to maintain a very low pressure in the exhaust system and thereby insure against air getting into the operating system.

It should now be apparent that when the port 97 is interconnected to the port 96 that the spring 103 will shift the tailstock center into engagement with a work piece and force the oil out of cylinder 99 into the return channel. Therefore the shifting of the footstock valve causes automatic insertion of the tailstock center into the end of the work and automatic starting of the headstock which causes rotation of the work. At the same time the valve 88 connects pressure to the infeed control valve 73, shifting the plunger 74 to the left as viewed in Figure 5, whereby the port 72 becomes interconnected with port 109. This results in the admission of pressure to channel 110 which has a branch connection to port 111 of a start and stop control valve 112 for the cam actuating piston 113 and a second branch connection to port 114 of the rapid traverse cylinder

38. The line 110 is also connected to the cylinder 38 through a parallel branch line connection 115 which has a check valve 116 serially arranged therein, the line 115 terminating in a second port 117 located in the cylinder 38. When the wheel head is in a retracted position the piston 40 covers the port 114 whereby the first admission of pressure to cylinder 38 must be through the check valve 116 which is set to offer a predetermined resistance to flow whereby the full pump pressure does not enter the cylinder at the beginning of the movement.

This produces a regulated acceleration of the wheel head until it has moved a sufficient distance that the piston 40 uncovers the port 114 whereby the pressure gradually builds up to full pump pressure and thus a maximum rate of movement of the wheel head.

The fluid in cylinder 39 is forced out to reservoir by movement of the wheel head through a control valve structure carried by the wheel head and comprising a valve sleeve 118 which is operatively connected to the rack piston 28 by a pin 119. The sleeve has an internal bore 120 in which is fitted a plunger rod 121 but the plunger rod is threaded at 122 in a fixed part 123 of the wheel head and locked against movement by a lock nut 124.

The plunger has two spools 125 and 126 separated by an annular groove 127. It should now be apparent that the rack piston 28 and the valve sleeve 118 remain stationary and the rest of the structure moves as a unit relative thereto.

The oil in escaping from the cylinder 39 passes through the passage 128, annular groove 129 and port 130 formed in the sleeve 118 to the annular groove 127 in plunger 121. The annular groove 127 interconnects the port 130 to port 131 which is drilled in the annular groove 132 of sleeve 118.

40. The annular groove is in constant communication with the port 133 which is the terminus of the channel 68. As the wheel head advances while the piston 28 and the sleeve 118 remain stationary, the spool 126 on the plunger 121 advances to 45 close port 130, thereby trapping the fluid in cylinder 39 which serves to decelerate the wheel head as it reaches the end of its rapid traverse stroke. The exhaust fluid flows through channel 68, interconnected ports 67 and 134 of the start and 50 stop valve 57, and return channel 135 to reservoir 62 through the low pressure relief valve 108.

The channel 110 which was connected to pressure by valve 73 has a branch connection to port 111 of valve 112 as previously mentioned and 55 urges the plunger 136 downwardly as viewed in Figure 5 simultaneously with the rapid traverse movement. This downward movement is retarded, however, by the enlarged piston 137 which operates against the back pressure in line 135.

60. The object of this is to retard the movement of valve plunger 136 until the wheel head has completed its rapid traverse movement, at which time the pressure in channel 110 will rise and thereby shift the plunger 136 faster to connect the pressure port 138 to port 139 and thereby through channel 140 to port 141 located in the end of cylinder 142.

The cylinder 142 contains the previously mentioned piston 113 which actuates the feed rate control cam 45. The piston is connected for operation of the cam in the following manner. Rack teeth 142' are formed longitudinally of the piston and in mesh with pinion 143 for driving the slide 144 which has similarly formed rack teeth 145 engaging the gear 143, Figures 5 and 8.

As viewed in Figure 5, the piston 113 in moving in the direction of arrow 113', causing the slide 144 and cam 45 to move in the direction of arrow 51 and the cam face 45, is so inclined as to cause movement of the follower 145' to the right, thereby permitting axial movement of the worm 33 under the constant pressure in cylinder 36, thus feeding the wheel head toward the work.

The fluid from the lower end of cylinder 142 exhausts through channel 146 which terminates in port 147 of the reversing valve 112. This port is connected by annular groove 148 to port 149 and channel 150 which leads to a rate control valve 151. This valve has a rotatable plunger 152 in which is formed a spiral throttling groove 153 for variably throttling the flow from port 154 to port 155. The port 155 is connected to the return channel 107. The rate valve plunger 152 terminates in a manual control 156 which is located on the front of the machine, as shown in Figure 1, and a graduated dial 157 is associated therewith to indicate the rate setting of the throttle valve.

The pinion 143 which transmits motion from the piston 113 to the cam 45 is secured to a shaft 158 and this shaft has keyed thereto a crank arm 159 in the end of which is an adjustable set screw 160 for engaging the end of a trip operated pilot valve plunger 161 which controls the shifting of the cycle reverse valve 79. This plunger has an enlarged central spool 162 and is normally held in the position shown by the constant fluid pressure in chamber 163 which is supplied by a branch channel 164 from channel 68 in which a back pressure exists as determined by the relief valve 108.

The crank arm 159 is rotated in a clockwise direction by the pinion 143 simultaneously with the movement of the cam 45 and at the end of the cam stroke it engages the end of the plunger 161 shifting it to the right as viewed in Figure 5. A port 165 which is constantly connected to a source of pressure acts on the enlarged spool 162 to complete the shifting of plunger 161 thereby hydraulically detenting it. The shifting of the plunger connects the port 165 to a port 166 and thereby through channel 167 to the tarry valve 168.

This valve is of the same construction as the rate valve and has a spiral throttling groove 169 for controlling the rate of flow from port 170 to port 171. The tarry valve is adjusted by a control knob 172 mounted on the front of the machine as shown in Figure 1 and provided with a dial 173 to indicate the setting thereof. The port 171 is connected by a channel 174 to port 175 located in the left end of the reverse valve 79. The object of the tarry valve is to delay the firing of the reverse valve plunger 80 a sufficient length of time to permit the grinding wheel to clean up the work, that is, to spark out. The pressure at port 175 must rise to a sufficient degree to overcome the pump pressure which constantly exists in the interior cylinder 84 of the plunger 80 as previously explained.

When this occurs the pressure port 81 of valve 79 is connected by annular groove 82 to a port 176 and thereby through channel 177 to port 178 of a fluid operable mechanism for returning the manual control valve and its control lever 54 to a combined reverse and stop position. This mechanism comprises a pair of telescoping plungers 179 and 180 which are constantly urged apart by a spring 181. A pin 182 limits the separation. The plunger 179 has rack teeth 183 formed there-

on which interengage the teeth on a gear 184 which is attached to the valve plunger of the valve 57.

Upon admission of pressure to port 178 the telescoping plungers move as a unit, thereby rotating the gear 183 and connected valve in a counterclockwise direction as viewed in Figure 5 and near the end of the stroke the plunger 179 uncovers a port 185 which is connected by channel 186 to an accumulator 187. The accumulator has a spring 188 which is adapted to yield under pressure whereby the plunger actuating fluid is adapted to expand into the accumulator and thereby momentarily reduce its pressure just as the valve reaches the end of its movement, thereby easing the shock on the valve as it reaches a positive stop, limiting its movement.

This rotation of the valve positions the vane 56 midway between the ports 58 and 69 whereby the pressure port 58 now becomes connected to the port 67 so that fluid pressure immediately flows through channel 68 to the rapid traverse piston.

At the same time the port 69 is interconnected to port 134 whereby channel 70 becomes an exhaust line. The spring 75 acting on plunger 74 is of sufficient strength to immediately shift the plunger to the right forcing the fluid through channel 93, valve 88 and resistance 86 to channel 70. This immediately connects channel 110 to exhaust port 193, thereby providing for free exhaust of fluid from the rapid traverse motor.

Since the port 130 is closed by the spool 126 the fluid pressure entering the annular groove 132 is forced to go through the passage 189 and check valve 190 to cylinder 39, the check valve causing a pressure drop which starts the wheel head slowly until the spool 126 uncovers the port 130 and opens up a bypass for the fluid around the check valve. The fluid in the other end of the cylinder escapes through port 114 since check valve 116 cannot open and the wheel head will move back at a fast rate until the tapered end 191 of piston 40 throttles the escape of fluid through port 114 and thereby causes deceleration of the wheel head until the piston 40 hits the end of the cylinder 38.

During the rapid return of the wheel head, fluid is continually passing through the resistance 86, lowering the pressure in line 93 to a point at which the headstock switch 95 will open. The spring 90 will then start to move the plunger 89 of the tailstock control valve until the port 97 becomes connected to the pressure port 100 causing the tailstock center 102 to be withdrawn from the work.

When the channel 110 is connected to exhaust by valve 73, it reduces the pressure in chamber 111 of valve 112 whereby the constant back pressure acting in the cylinder 137 is enabled to shift the plunger 136 upward, thereby connecting the port 139 leading from the upper end of cylinder 142 to exhaust, and port 147 to pressure port 138 whereby actuating fluid will enter the lower end of cylinder 142 and effect return movement of piston 113 and connected cam 45.

The cam 45 will effect axial movement of worm 33 against the pressure in cylinder 36 and thereby additional retraction of the wheel head.

At the same time the counterclockwise rotation of the pinion 143 will cause counterclockwise rotation of the crank arm 159 and since constant pressure is now admitted to the cylinder 163 the plunger 161 will be shifted to the left, thereby disconnecting the pressure port 165 from port

166. The latter port becomes connected to port 194 which is connected to the back pressure reservoir line 135 and this maintains the line 167 full of fluid, thereby preventing the admittance of air which might affect the feed rate on the next operation. All the parts have now returned to their starting position.

A brief summary of the sequence of events during an automatic infeed cycle is as follows. The throwing of the lever 54 to its start position connects fluid pressure to the footstock valve causing the plunger thereof to move at such a rate that the footstock center will engage and pick up a work piece, it being understood that the work will normally be placed upon a suitable work rest of proper height so that the center 102 in moving forward will push the work on to the headstock center and at the same time lift the work sufficiently to clear the work rest. It should be apparent that the work must be properly held between centers before anything else occurs. Having accomplished this, the tailstock center continues its movement and opens port 92 which thereby shifts the infeed control valve plunger and operates the pressure switch 95 to start the work rotating. The infeed control valve connects pressure to the rapid traverse motor which moves the wheelhead in and at the same time connects pressure to the reversing valve for the feed rate control motor so that as soon as the rapid traverse movement is completed the feeding movement may start.

The feed rate control piston 113 moves the cam 45 at a selected rate as determined by the setting of the control valve 151 and by the time the feeding movement is completed the cam 45 has moved out of engagement with its follower, the worm shaft has engaged the positive stop 44 and the crank arm 159, has tripped the pilot valve 161. Fluid pressure is now admitted by way of channel 167 and tarry valve 168 to the reversing valve 79 which eventually shifts to effect return of the control lever 64 to its stop position. This results in port 69 being connected to reservoir and port 67 being connected to pressure whereby the rapid traverse motor immediately starts return movement of the wheel head. Due to the connection of port 69 to reservoir, pressure is immediately relieved in the footstock valve as well as in the infeed control valve and the pressure switch 95 whereby the pressure switch goes off to immediately stop rotation of the work and the infeed control valve plunger 74 shifts to the right to relieve the pressure in valve 112 so that the plunger 136 can shift to connect the pressure port 138 to port 147 and thereby cause return movement of the feed rate piston 113. This produces an additional return movement, in addition to the rapid traverse movement, and the movement of the tailstock valve plunger is timed to be returned when these movements have ceased to withdraw the tailstock center from the work.

In addition to the mechanism for actually effecting the automatic infeed cycle, certain controls and interlocks have been provided whereby this mechanism may be utilized together with, or independent of, the table traversing mechanism.

The power traversing of the table is controlled by the table start and stop valve which is operated by the lever 24, a reversing valve 195 and a pilot valve 196, Figure 6. The reversing valve 195 has a pressure port 197 to which the pump supply line 59 is connected, and a pair of motor

ports 198 and 199 which are connected through the table control valve as shown in sections 18 and 20 thereof in Figure 6 to the motor lines 200 and 201 respectively. In other words, the table start and stop valve has a pair of ports 202 and 203 to which the lines 204 and 205 from ports 198 and 199 are connected, and when the valve plunger 23 is rotated clockwise to its start position, port 203 is connected by groove 206 to port 207 and thereby line 201, and port 202 is connected by groove 208 to port 209 and thereby to line 200.

The reversing valve 195 has a plunger 210 in which is formed a pair of annular grooves 211 and 212 for alternately connecting the pressure port to ports 198 and 199 respectively and for simultaneously connecting the remaining port to port 213 or 214, depending upon the direction of shift of the plunger. These ports are alternately connected to a common return line 215 which leads to a feed rate throttle valve 216 by the plunger 217 of the pilot valve 196 which also controls the shifting of the reversing valve plunger 210.

In other words, the ports 213 and 214 are connected by channels 218 and 219 to ports 220 and 221 of the pilot valve and the annular grooves 222 and 223 in the pilot valve plunger are alternately positioned to connect the ports 220 and 221 to the common exhaust port 224 to which the line 215 is connected. The pilot valve also has a pair of pressure ports 225 and 226 whereby as the plunger shifts and immediately after it passes through its center position it will connect a shot of pressure to the exhausting side of the table motor to assist in stopping it before the reversing valve is shifted.

The pilot valve has a pressure port 227 which is flanked by a pair of ports 228 and 229 which are connected by channels 230 and 231 to ports 232 and 233 located in opposite ends of the reversing valve housing 195. The plunger 217 is provided with an enlarged spool 234 which is movable relative to the pressure port 227 so that after passing the port a force component sufficient to complete the shifting of the plunger 217 is produced. This acts in the nature of a hydraulic detenting mechanism. A crank arm 235 is operatively connected to the plunger for shifting the same, the crank arm being keyed to the end of a trip shaft 236 which carries a trip lever 237 on the upper end thereof as shown in Figure 1 for actuation by trip dogs 238 and 239 carried by the table 13.

It is desirable that a delayed reversing action be effected in the table and to that end each of the channels 230 and 231 have delay valves 240 and 241 serially arranged therein. These valves operate to restrict the flow to the reversing valve but any return flow is by-passed around these valves by means of check valves 242 and 243 which are directionally connected to open under a return flow from the reversing valve, but which will close upon a flow to the reversing valve and thereby force the fluid to pass through the delay valves. The ports 228 and 229 are alternately connected to exhaust ports 244 and 245 which are connected to the return line 107.

In addition to effecting shifting of the reversing valve, the pilot valve also functions to effect actuation of a power operable pick feed mechanism, indicated generally by the reference numeral 246 in Figure 5 of the drawings. This mechanism comprises a reciprocable piston 247 which is slidably mounted in a cylinder 248.

The opposite ends of the cylinder are connected by channels 249 and 250 to a reversing valve 251. The reversing valve has a plunger 252, the shifting of which is controlled by the table pilot valve 196 by connecting the end ports 253 and 254 to the pilot valve ports 228 and 229 by channels 255 and 256. Each of the channels 255 and 256 has a pair of parallel connected check valves 257 and 258 but oppositely directed whereby one valve closes and the other opens upon a flow to the reversing valve, and vice versa upon a flow from the reversing valve. The channels 255 and 256 also conduct pressure for shifting the piston 247. With the parts in the position shown it will be noted that the pressure port 227 of the pilot valve is connected to channel 255 and this channel has branch connections to ports 259 and 260 of the reversing valve. With the plunger 252 in the position shown the port 260 is connected by an annular groove 261 to port 262 and thereby to channel 250 whereby the fluid pressure from port 227 holds the piston 247 in the position shown. Upon shifting of the pilot valve plunger the port 227 becomes connected to port 229 and fluid pressure enters channel 256. This channel has branch connections to ports 263 and 264 of the reversing valve and the port 263 is connected by the annular groove 265 to port 266 and thereby to channel 267.

This channel leads to port 268 of a start and stop valve 269, which valve serves to stop operation of the pick feed mechanism. With the valve plunger 270 of this valve in the position shown the port 268 is connected by an annular groove 271 to port 272 and channel 249 to the cylinder 248. The channel 249 has a resistance 273 serially arranged therein to retard operation of the piston 247 sufficiently to prevent hammering.

It will now be apparent that upon shifting of the pilot valve, fluid pressure is immediately admitted to cylinder 248, causing actuation of the piston 247 and thereby operation of the pickfeed mechanism, the check valve 257 functioning to retard the admittance of pressure to port 254 and thereby the shifting of the plunger 252 until the piston 247 has completed its movement. When this occurs the plunger 252 completes its shifting movement, closing port 263 but opening port 264. This port then becomes connected by way of annular groove 274 to port 275 and thereby to channel 250. This admits fluid pressure to the other end of cylinder 248 and returns the piston 247 to its starting position. Therefore upon a single shifting movement of the pilot valve plunger the piston 247 is caused to execute a complete reciprocation.

The same effect is produced when the pilot valve plunger 211 is shifted in the other direction, only the pressure is connected this time to channel 255 and the plunger 252 is in position to connect port 259 to port 276 whereby the fluid will again flow to channel 267 and from there on through the same path to the cylinder 248 shifting the piston 247 to the left. While this is going on, pressure will be slowly leaking through the check valve 257 to shift the plunger 252 toward the right and when the piston 247 reaches the end of its stroke the pressure will rise to complete the shifting movement. This will close the port 259 and will interconnect port 260 to port 262 and thereby return the piston 247 to its starting position.

The piston 247 has rack teeth 277 which intermesh with a gear 278 which is supported for free rotation on a shaft 279. The gear is integral with

an arm 280 that carries a pawl 281. The pawl 281 has a heel 282 which is adapted to engage an abutment 283 upon counterclockwise rotation of the arm 280 and thus serves to withdraw the pawl from engagement with the periphery of a ratchet wheel 284.

Upon clockwise rotation of the arm 280 the pawl 281 will drop into engagement with the ratchet wheel 284 and effect rotation of the shaft 10 279. The ratchet wheel 284 has a gear 285 formed integral therewith and this gear intermeshes with a gear 286 which is supported on a shaft 287 and is adapted to be connected to the shaft for rotation of the gearing 47 and thereby of the worm 33.

15 The gear 286 carries means for stopping operation of the pick feed mechanism which comprises a button 288 which is so positioned that it will engage the pointed end of the plunger 270 and shift the same to the left as viewed in Figure 5. The plunger carries an enlarged spool 289 which is movable relative to a pressure port 290 whereby after the spool passes the pressure port the admittance of pressure to the other side of the spool will complete the shifting movement in the direction in which the plunger happens to be moving. This functions as a hydraulic detent mechanism to hold the plunger in either one of its two positions. When the plunger 270 is shifted to the left it closes the port 268 and interconnects the port 272 with a return port 291.

The result of this is to stop the hydraulic impulses in line 267 from being communicated to the piston 247 and at the same time to connect the channel 249 to the back pressure exhaust line 35 which maintains sufficient fluid in channel 249 to prevent the entrance of air into the system.

It will be apparent that it is impossible to reset the plunger 270 manually and therefore hydraulic means are provided for this purpose after gear 286 has been rotated to remove the button 288 from the path of the plunger. This mechanism comprises a reset valve 292 which has a pressure port 293, an exhaust port 294 and a third port 295 which is connected by channel 296 to port 297 located in the left end of the valve 269.

The plunger 298 is held in the position shown by a spring 299 and a shoulder 300 formed on the end of the plunger for engaging the end of the sleeve 301. This positions the valve to connect the port 295 to the exhaust port 294 whereby the plunger 270 may be shifted to the left without undue resistance. When the plunger 298 is depressed, the port 295 is connected to the pressure port 293 which thereby admits fluid pressure to the port 297, shifting the plunger 270 to the right.

It will be understood that after the pick feed mechanism has stopped operating that the table will make one or more reciprocations and that 60 actual stopping of the table will be effected by the operator who will throw the manual control lever 24 to its stop position and in so doing he will rotate the valve plunger 23 in a clockwise direction to the position shown in Figure 6.

65 This will result in pressure being connected to both ends of the cylinder 15, thereby equalizing the pressure on both ends of the piston and thereby making it possible to effect manual operation of the slide 13.

The mechanism for manually operating the table is shown in Figure 3. This mechanism comprises a hand wheel 302 which is fixed to the end of a shaft 303 that carries a gear 304. The shaft 303 is adapted to be axially moved in its bearings 305 and 306 whereby the gear 304 may be engaged

with a gear 307 for slow operation of the table 13 or may be interengaged with internal gear teeth 308 of a gear 309 to effect fast movement of the table. A spring pressed detent 310 is provided for holding the shaft in either one of its two positions. When the gear 304 is intermeshed with the gear 307 the drive is then through a train comprising a gear 311 integral with the gear 307, gear 309, pinion 312, gear 313 and gear 314 which is integral therewith, and idler 315 which is interposed between the gear 314 and a rack 316 which is attached to the underside of the table.

When the shaft 303 is shifted to the right, the gear 304 engages the internal gear 308 in the manner of a clutch whereby the gear 309 is rotated directly by the shaft 303. Since the gear 312 is integrally connected to the gear 309 the drive is then through gear 313, pinion 314 and idler 315 to the rack 316. The gears 313 and 314 are capable of axial movement but are normally held in the position shown by a spring 317 which is interposed between them and extends into bores 318 and 319 formed in the opposing faces thereof. A spacing rod 320 is mounted within the spring to limit the movement of the gear 313. The purpose of this construction is to shift gears 313 and 314 to the left and thereby disengage the gear 314 from the gear 315 so that it is impossible to attempt to effect manual operation of the table while it is being power driven, or on the other hand to prevent rotation of the hand wheel 302 during power actuation of the table.

The gear 313 has an elongated hub 321 by which it is journaled in the bearing 322 and the hub has a reduced portion 323 which slides in a bearing 324 and also extends into a chamber 325 to act as a piston for shifting the two gears, the gear 314 being pinned to the reduced portion 323. The chamber 325 is connected by a channel 326 to port 327 of the table start and stop control valve. When this valve is in the stop position in which it is shown the port 327 is connected to an exhaust port 328 which thereby relieves the pressure in chamber 325 but when the valve is rotated in a clockwise direction the pressure port 329 is connected to the port 327 and thereby to the chamber 325. Thus, there is an interlock to disconnect the manual actuating mechanism from the work table during power actuation thereof.

There is an additional interlock on the table start and stop control valve which prevents the starting of the table until the wheelhead has been moved into engagement with the positive stop 44. This is a precautionary measure to insure that all sizing of the work is done with the wheelhead in engagement with the same stop. To this end the valve plunger 23 is provided with a locking notch 330 which is adapted to be engaged by a spring pressed locking plunger 331 which when in position will prevent clockwise rotation of the plunger 23 to a starting position. The locking plunger is slidably mounted in a housing 332 and is normally held in position by a spring 333 located between an enlargement 334 on the plunger and the end of the housing. The enlargement 334 being greater in diameter than the locking portion 331, serves to provide a differential area 335 which may serve as a piston to effect withdrawal of the pin 331 against the resistance of the spring 333. To this end the housing is provided with a port 336 to which is connected a channel 337, that is, a branch of the channel 140 that supplies

the infeed piston 113 as shown in Figure 5. Therefore, when the infeed piston 113 is being actuated under pressure the locking pin 331 is withdrawn so that the start and stop valve may be operated. The purpose of this is that during an infeed grinding operation it may be desirable to effect a small reciprocation or oscillation of the work with respect to the grinding wheel, especially in cases where the axial length of the surface being ground is a little greater than the width of the grinding wheel.

For conventional reciprocating grinding operations the infeed rate valve 152 is opened wide and the tarry valve 168 is closed with the result that when the infeed start lever 54 is thrown to the start position the rapid traverse piston and the infeed piston 113 move quickly to their end positions without delay whereby the positive stop is immediately engaged to insure a positive positioning of the grinding wheel.

It should be noted that this operation also causes engagement of the tailstock center as well as the closing of the headstock switch 95 which produces rotation of the work and since the interlock pin 331 has been withdrawn the operator may now throw the lever 24 to its start position to cause reciprocation of the table. The wheel 46 is now rotated to move the grinding wheel into engagement with the work and then the pick feed mechanism is set into operation to complete the grinding operation.

It should be noted that the positive stop serves as the ultimate limit of movement of the grinding wheel during an infeed grinding operation, but during a reciprocating cycle it serves merely as a positive abutment from which to start the infeeding of the grinding wheel.

When a reciprocating cycle has been completed the operator may move the grinding wheel out of engagement with the work and simultaneously stop the table by a single movement of the table control lever 24. This is accomplished by moving the lever, not only to the stop position but to a third position previously referred to as the dash and dot line 26 shown in Figure 1. The effect of this is to rotate the valve plunger 23 a sufficiently additional distance in a counter-clockwise direction to connect a pressure port 338 to port 339 in section 21 of the valve and thereby to channel 340 which leads to port 175 of the reversing valve 79 shown in Figure 5. The shifting of this valve as previously explained in connection with the infeeding cycle, connects pressure to the channel 177 which results in the throwing of the infeed cycle control lever 54 to its stop position, thus causing immediate retraction of the grinding wheel.

When the wheel head is returned in this manner it can only be brought back in again by operation of the infeed control lever 54. It is to be noted that any time this lever is utilized to advance the wheel head and the feed rate throttle valve 152 is set for a feed rate, that the throttle valve may be bypassed to obtain a fast rate of movement by merely throwing the lever beyond its normal infeed position. When this is done a drilled passage 341 in the valve plunger interconnects port 342 which is branch connected to line 150 with exhaust groove 343 and port 67 to the return line 135. This provides an open passage to reservoir, thereby momentarily eliminating the effect of the feed rate valve.

In addition to adjusting the feed rate by the throttle valve 152, major changes may be made in the rate by changing the angularity of the

cam without changing the setting of the throttle valve. Angularity changes are made more particularly, however, for changing the length of the feed movement.

The means for changing the angularity of the cam is shown more particularly in Figures 7, 8 and 9. The cam 45 is mounted in a U-shaped holder 344 as shown in Figure 8. The holder bears against two rollers 345 and 346 and is operatively connected to the rack 144 by a pin 347. The pin carries a block 348 which fits in a slot 349 formed in the back of the cam 45 for transmitting motion to the cam. The cam is backed up by two stops 350 and 351 and held against the stops by the hydraulically actuated follower roller 145'. The stop 351 is keyed at 352 to an adjusting shaft 353.

The various sides of the hexagon are different distances from the center beginning with the side 354 which is closest to center and which effects the smallest angularity of the cam. The distances of the sides 355, 356, 357, 358 and 359 from the center increase by the same increment in the order named.

The shaft 353 has a knurled operating knob 360 whereby the stop 351 may be rotatably adjusted to any one of six positions to obtain different lengths of infeed for the same length of movement of the cam.

A stop screw 361 limits the movement in one direction which is the feeding movement whereby the cam always stops in the same position and which is such that the cam is just out of engagement with the follower roller so that the positive stop 44 shown in Figure 2 is always effective.

The length of cam stroke is determined by an adjustable stop 362 shown in Figure 5 and having a threaded connection with the shaft 363 which is actuated through bevel gears 364 and 365 from the hand wheel 366 mounted on the end of shaft 367 splined in gear 365. The shaft 363 has a splined connection with gear 364 so that a piston 368 on the end of the shaft sliding in cylinder 369 may act as a dashpot to cushion the shock. The cylinder is connected to pressure at all times.

Referring to Figure 4, the length of the infeed increments effected by the pick feed mechanism may be varied by adjusting the stop 370 longitudinally of the cylinder 248. The stop has an angular end 371 engaging the angular surface 372 on the threaded member 373. A threaded adjusting shaft 374 interengages therewith and has an operating knob 375.

The shaft 374 has a gear reduction connection 376 to a graduated dial 377. Thus, by rotating the knob 375, the stop is adjusted and the dial rotated simultaneously.

There has thus been provided an improved actuating and control mechanism for a grinding machine which greatly improves the operation thereof, and which is highly selective whereby the various types of grinding operations may be carried out automatically.

What is claimed is:

1. In a grinding machine having a fixed support, a work support and a grinding wheel support mounted thereon for relative movement in angularly related directions, the combination of means for advancing one of said supports toward and from the other including a worm rotatably mounted in the fixed support and having a limited axial movement relative thereto, a control cam, means for continuously urging the worm into engagement with said cam, a worm wheel engaging the worm and operatively connected for

transmitting movement to the grinding wheel support, said connection including a rack piston slidably mounted in the grinding wheel support, means to apply fluid pressure to said piston to effect rapid movement of the grinding wheel support, and means to move said cam to effect a feeding movement of the grinding wheel support.

2. In a grinding machine having a fixed support, a work table and a wheelhead mounted on said support for relative movement in angularly related directions, a headstock and a tailstock carried by the table including centers for supporting work for relative rotation with respect to the grinding wheel carried by the wheel head, the combination of control means for governing movement of the wheel head including a rapid traverse piston and a feed piston, a source of fluid pressure, a start and stop valve adapted when moved to a starting position to connect said source of pressure to the rapid traverse piston, fluid operable means for retracting the tailstock center, a tailstock control valve normally in a position to connect said source of pressure to said fluid operable means, means in the starting valve for connecting fluid pressure for shifting said tailstock control valve to release the pressure on said tailstock center, resilient means for advancing the tailstock center when pressure released, an infeed control valve fluid actuated upon shifting of the tailstock control valve for connecting pressure to the rapid traverse piston, a reversing valve for the feed piston adapted to be shifted by said pressure to initiate operation of the feed piston, and means operable by the feed piston for imparting a slow rate of movement to the wheel head.

3. In a grinding machine having a work supporting table and a grinding wheel slide, the combination of a table motor, a rapid traverse motor and a feed motor for the wheel head, a source of fluid supply for all of said motors, a first valve for connecting said source to the rapid traverse motor to effect quick advance of the wheel head, additional valve means automatically operable to connect fluid to said feed motor to effect additional advance of the wheel head, means to regulate the rate of movement of said feed motor to a slow rate for infeed grinding purposes, or at a rapid rate for traverse grinding purposes, a third valve for connecting said source of pressure to the table motor, means normally locking said third valve, and fluid operable means controlled by said additional valve means for releasing said locking means after the wheel head has completed its rapid traverse movement.

4. In a grinding machine having a fixed support, a work table slidably mounted on the support, and a wheel head slidably mounted on the support for movement toward and from the table, the combination of means for advancing and retracting the wheel head relative to the table including a cylinder formed in the wheel head, a piston slidably mounted in the cylinder, means in the fixed support for holding the piston against movement whereby the admission of pressure to either end of the cylinder will cause movement of the wheel head, a valve member slidably mounted in the wheel head and operatively connected to said piston, portings in the wheel head controlled by said valve member during advance of the wheel head to decelerate the wheel head, and bypass check valve connections paralleling said portings to initiate return movement at a prescribed accelerated rate.

5. In a grinding machine having a fixed support, a work table slidably mounted thereon, and a wheel head supported for movement toward and from the work table, the combination of means for shifting the wheel head including a worm mounted in the fixed support for rotation and axial movement, means operatively connecting the worm to the wheel head, means for holding the worm against axial movement including a cam mounted at one end of the worm and a hydraulic piston mounted at the other end of the worm for holding the same against the cam, means to move the cam at a prescribed rate to effect axial shifting of the worm and thereby infeeding of the wheel head, and a fixed positive stop for ultimately limiting movement of the worm independent of the cam.

6. In a grinding machine having a fixed support, a work table slidably mounted thereon and a wheel head supported for movement toward and from the work table, the combination of means for shifting the wheel head including a worm mounted in the fixed support for rotation and axial movement, means operatively connecting the worm to the wheel head, means for holding the worm against axial movement including a cam mounted at one end of the worm and a hydraulic piston mounted at the other end of the worm for holding the same against the cam, means to move the cam at a prescribed rate to effect axial shifting of the worm and thereby infeeding of the wheel head, fluid operable means for shifting said cam, and a throttle valve for said fluid operable means to determine the rate of cam movement.

7. In a grinding machine having a fixed support, a work table slidably mounted thereon, and a wheel head supported for movement toward and from the work table, the combination of means for shifting the wheel head including a worm mounted in the fixed support for rotation and axial movement, means operatively connecting the worm to the wheel head, means for holding the worm against axial movement including a cam at one end and a hydraulic piston at the other end of the worm, means to move the cam at a prescribed rate to effect axial shifting of the worm and thereby infeeding of the wheel head, a fixed positive stop for ultimately limiting movement of the worm independent of the cam, and means to rotate said worm to change the relative position of the wheel head with respect to the actuating mechanism and thereby change the zone of movement relative to the work.

8. In a grinding machine having a bed, a table and a grinding wheel support slidably mounted on the bed, and a grinding wheel rotatably mounted on the grinding wheel support, the combination of means for advancing and retracting the wheel relative to the table for either infeed or traverse grinding operations including a fluid operable motor, supply and return lines for the motor having a reversing valve interposed therein, fluid operable means for shifting said valve including a trip operated pilot valve, a delay valve interposed between the pilot valve and reversing valve for delaying the shifting of the latter, and means to close said delay valve for preventing operation of the reversing valve when the motor is utilized for advancing the wheel head for traverse grinding operations.

9. In a grinding machine having a bed, a work support mounted on the bed for traverse movement, and a grinding wheel support, the combination of means for advancing the grinding

wheel support to and from the work support including a fluid operable motor, a fluid control circuit for said motor including a cycle control valve, manually operable means for positioning said valve to initiate a cycle, a pilot valve, a cycle reversing valve and a motor reversing valve arranged in said circuit, means operable by the motor for shifting said pilot valve to effect shifting of the cycle reverse valve, and means responsive to shifting of the cycle reverse valve for shifting the motor reversing valve to reverse the actuation of said motor.

10. In a grinding machine having a work supporting table and a grinding wheel support, the combination of a control circuit for controlling relative movement between the supports including a table operated pilot valve, a table reversing valve, a pick feed mechanism for the grinding wheel support including a reversing valve therefor, means controlled by the pilot valve to effect shifting of said table reversing valve, said pick feed mechanism including a fluid operable piston, a cylinder containing said piston, a pair of channels leading to opposite ends of the cylinder, a blocking valve in one of said channels, and means trip operable by the pick feed mechanism for shifting said blocking valve to stop operation of the pick feed mechanism.

11. In a grinding machine having a work supporting table and a grinding wheel support, the combination of a control circuit for controlling relative movement between the supports, comprising a pick feed mechanism for the grinding wheel support including a reversing valve therefor, said pick feed mechanism including a fluid operable piston, a cylinder containing said piston, a pair of channels leading to opposite ends of the cylinder, a blocking valve in one of said channels, means trip operable by the pick feed mechanism for shifting said blocking valve to stop operation of the pick feed mechanism, a hydraulic detent for holding said blocking valve in a stop position and fluid operable means including a control valve for resetting said blocking valve in running position.

12. In a machine tool having relatively movable work and tool supports, the combination of means for effecting a relative idling movement between said supports in a direction to bring the tool on the tool support into engagement with the work on the work support including a constant stroke piston and cylinder mechanism, a manually operable control valve for connecting pressure to said mechanism to cause said movement, a second piston operatively connected for shifting said mechanism as a unit for causing additional movement of the support, a control cam opposing movement by said second piston and a fluid operable control circuit for feeding said cam at a constant predetermined rate to control the rate of movement imparted by said second piston.

13. In a machine tool having a work support and a tool support, the combination of an infeeding mechanism for causing a relative infeeding movement between said supports including a constant stroke piston and cylinder mechanism, a manually operable control valve for connecting pressure thereto, a second piston for imparting additional movement at a feed rate including a reversing valve therefor normally held in one position, a cycle control valve remotely controlled by said manually operated control valve for connecting pressure to shift said reversing valve, and pilot control means trip operated by the second-named piston to cause power actuation of said

manual control valve and thereby a relative separation between said supports.

14. In a grinding machine having a work support, a grinding wheel support and power operable means including a control lever for starting and stopping movement of the work support, the combination with an interlocking member normally holding said lever in a stop position, of power operable means for moving the grinding wheel support including a rapid traverse mechanism and a feed mechanism, control means for connecting a source of power to the rapid traverse mechanism, and means for subsequently and automatically connecting power to the feed mechanism and simultaneously to said interlocking means to effect release of the interlock whereby the work support may be traversed during the feeding movement of the grinding wheel support.

15. In a machine tool having movable work and tool supports, power operable means for moving one of said supports and other power operable means for moving the other of said supports, the combination with a control for starting and stopping the first-named power operable means, of an interlock normally positionable for holding the control in its stop position, a second control member shiftable for connecting power to said other power operable means and simultaneously effecting withdrawal of said interlock whereby one support may be traversed during movement of the other support.

16. In a grinding machine having a work support, a grinding wheel support and power operable means including a control lever for starting

and stopping traversing of the work support, the combination with an interlocking member normally positioned to hold the control lever in a stop position, of a first fluid operable means for moving the grinding wheel support at a fast rate, a second fluid operable means for controlling movement of the grinding wheel support at a feed rate, means for connecting fluid pressure to said first-named fluid operable means, a control valve responsive to the fluid pressure connected to said first-named fluid operable means for connecting fluid pressure to said second-named fluid operable means, a fluid pressure actuator for releasing said interlocking member, said control valve also connecting fluid pressure for releasing said interlock.

17. In an infeed mechanism for the grinding wheel support of a grinding machine having a pressure operated member operatively connected to the support for producing an infeeding movement thereof, the combination of means for controlling the rate of operation of said movement including a slideable feed control cam, a cam follower urged by said fluid pressure operated member into engagement with said cam normal to its direction of movement thereof, a pivotal support for one end of said cam, an adjustable stop member engaging the other end of said cam for varying the angularity thereof about its pivot and thereby the length of feeding movement effected for a given movement of the cam, and control power operable means for shifting the cam mechanism transversely to the axis of said follower.

JACOB DECKER.
ALBERT D. C. STUCKEY.
